CLAIM

The ornamental design for a side-mounted throttle and weapons controller for video games and flight simulators, as shown and described.

DESCRIPTION

FIG. 1 is a right side perspective view of a side mounted throttle and weapons controller for computer video games and flight simulators, according to the design of the present invention;

FIG. 2 is a right side elevation view of the controller of FIG. 1;

FIG. 3 is a left side elevation view of the controller of FIG. 1;

FIG. 4 is a rear elevation view of the controller of FIG. 1;

FIG. 5 is a front elevation view of the controller of FIG. 1;

FIG. 6 is a top plan view of the controller of FIG. 1; and,

FIG. 7 is a bottom plan view thereof.
